UNITED STATES PATENT OFFICE

2,466,081

CHAIR

Victor J. Colvez, Minneapolis, Minn.

Application August 3, 1945, Serial No. 608,744

5 Claims. (Cl. 155—99)

1

This invention relates to new and useful improvements to chairs, and more particularly to chairs of the general character disclosed in my co-pending application, Serial No. 586,209, filed April 2, 1945.

An object of the present invention is to provide a reversible chair comprising a supporting base and a combination seat and back unit which is swingably mounted upon the base in such a manner that the seat and back portions of said unit may be quickly interchanged with respect to the base.

A further object is to provide a reversible chair comprising a supporting base having front and rear frame members, and a combination seat and back unit being mounted for pivotal movement in horizontal and vertical planes upon the rear frame member, whereby the seat and back portions of said unit may be conveniently reversed or interchanged with respect to the base to thereby more uniformly distribute wear on said seat and back portions, and also whereby the general appearance of the chair may be varied, particularly if the seat and back portions are upholstered with materials of different patterns.

A further and more specific object of the invention is to provide a chair of the class described comprising a supporting base having front and rear frame members, and an upright or vertical pivot being mounted in the rear frame member intermediately of the ends thereof and carrying an elongated member having bearing portions at its ends, and a combination seat and back unit of symmetrical configuration having its rear central portion provided with suitable bearings adapted to receive the bearing portions of the elongated member, whereby the seat and back unit is adapted for swinging movement upon the base in two directions, thereby to permit the seat and back portions to be conveniently reversed or interchanged with reference to the base, when so desired.

Other objects of the invention reside in the simple and inexpensive construction of the means for pivotally supporting the combination seat and back unit upon the base; in the provision of a reversible chair provided with permanent front and rear portions, an having a combination seat and back unit mounted for swinging movement on the rear frame member to permit the seat and back portions of said unit to be reversed or interchanged; in the provision of means on the front base frame member for locking the combination seat and back portion in adjusted position on the base; and in the simplified construction

2

of the chair as a whole, whereby it may be manufactured in quantity production at extremely low cost, and which chair, when in operative position, will have the appearance of a conventional chair and may be so handled.

Other objects of the invention will appear from the following description and the accompanying drawings and will be pointed out in the annexed claims.

10 In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a side view of my improved chair partially broken away to more clearly disclose 15 the construction thereof;

Figure 2 is a rear view of the chair partially broken away to show the pivotal mounting of the seat and back unit upon the base;

Figure 3 is a view similar to Figure 1, but showing the combination seat and back unit partially tilted rearwardly;

Figure 4 is a view showing the seat and back unit rotated to an angle of approximately 90° with reference to the base, a position assumed 20 during the reversing of the seat and back unit;

Figure 5 is a view showing the seat and back unit swung a half revolution with reference to the base, and in position to be tilted forwardly to complete the reversing of the seat and back unit upon the base; and

25 Figure 6 is a view similar to Figure 1, but showing the seat and back unit in reversed position to the position shown therein.

In the selected embodiment of the invention 30 herein disclosed, there is illustrated in the drawings a chair comprising a supporting base, generally designated by the numeral 2, comprising front and rear frame members 3 and 4, respectively, connected together by suitable side frame members 5 and 6. The base may be supported upon suitable front and rear legs 7 and 8, and, if desired, may be covered with suitable upholstering, as indicated for example at 9.

An important feature of the present invention 35 resides in the novel construction of the upper portion of the chair which comprises a combination seat and back unit, generally designated by the numeral 11. The unit 11 comprises a suitable supporting frame providing angularly disposed portions A and B which preferably are uphol-

stered to provide seat and back portions 12 and 13, respectively, as in Figures 1, 3, 5 and 6.

When the combination seat and back unit 11 is positioned, as shown in Figure 1, the portion A thereof provides the seat of the chair and the portion B the back. The end portions of the seat and back parts A and B, when viewing the chair, as shown in Figure 1, are provided respectively with cross frame members 14 and 15, and their opposite or connected end portions are connected together by cross frame members 16 and 17, respectively, as shown.

Another important feature of the invention resides in the pivotal mounting of the unit 11 upon the supporting base 2, whereby its position upon the base may be conveniently interchanged or shifted to reverse the positions of the seat and back portions A and B, as will subsequently be described.

To thus pivotally support the unit 11 upon the base 2, an upright or vertical pivot 18 is mounted in the rear frame member 4 of the supporting base, and supports at its upper end an elongated member or rod 19 having its central portion engaged with the pivot pin 18, whereby the rod or member 19 is adapted for swinging movement about the axis of the pin 18 in substantially a horizontal plane.

The lower rear corners of the combination seat and back unit 11 are provided with suitable bearings or sockets 21 and 22 adapted to receive the terminal bearing portions of the elongated member 19, as will be understood by reference to Figures 3, 4 and 5. By thus mounting the unit 11 upon the supporting base 2, the seat and back unit may readily be reversed upon the base without effort, and when secured in adjusted position upon the base, as shown in Figures 1 and 6, the chair will have the appearance of a conventional chair and may be moved about in a room in a similar manner.

To lock the combination seat and back unit in adjusted position upon the base, a suitable lock screw 23 may be mounted in an angle bracket 24 or similar supporting device provided on the inside surface of the front frame member 3, as best shown in Figure 4. The threaded terminal of the screw 23 is adapted to be selectively received in threaded sockets 25 provided in the end frame members 14 and 15 of the frame of the unit 11. The screw may readily be manipulated by extending an arm under the front rail or frame member 3 of the base and upwardly, as will be understood.

In Figure 1 the combination seat and back unit is shown secured in operative position upon the base with the portion A thereof forming the seat of the chair and the portion B the back thereof.

In Figure 3 the locking screw 23 is shown disengaged from the threaded socket 25 in the cross rail 14, and the unit 11 partially tilted rearwardly, in the initial step of reversing the unit A from the position shown in Figure 1 to the position shown in Figure 6.

In Figure 4, the combination seat and back unit has been turned to a position of about 90° with reference to the base, and

In Figure 5 it is shown rotated about 180° about the vertical pivot 18 from which position it is tilted forwardly, as indicated by the arrow 10 to the position shown in Figure 6, thereby reversing the seat and back portions of the unit 11, as will be noted by reference to Figure 6. When the unit 11 has thus been reversed with reference to the base, the lock screw 23 is moved into

locking engagement with the cross rail 15, thereby fixedly securing the combination seat and back unit to the base, whereby the chair may readily be moved about from one place to another as an ordinary chair.

The means for mounting the combination seat and back unit upon the base is extremely simple and inexpensive, whereby it does not add particularly to the manufacturing cost of the chair.

10 Because of the combination seat and back unit 11 being readily reversible, as herein disclosed, the chair is given much longer life, because wear upon the upholstering 12 and 13 is more evenly distributed, and the same applies to the upholstering which may be provided for covering the frame of the unit 11, as indicated at 26 in Figures 1 and 6.

In the drawings I have shown the elongated member 19 as extending substantially the full width of the seat and back unit. It is to be understood that this member may be made shorter and the bearing portions 21 and 22 of the unit 11 may be moved inwardly towards the center of the chair to a position shown in Figure 4, without departing from the scope of the invention. The pivot pin 18 and elongated member 19 thus cooperate to provide free swinging movement of the seat and back unit upon the base with a minimum of parts, and whereby the unit 11 may be quickly reversed upon the base for the reasons herein stated, when desired.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

45 1. In a chair of the class described, a suitable base including front and rear frame members, a combined seat and back unit including seat and back portions secured together in angular fixed relation, and pivot means at the intermediate portion of the rear frame member for pivotally mounting the seat and back unit on the base and whereby the seat and back unit is adapted for swinging movement in horizontal and vertical planes, thereby to permit positioning said unit to reverse the seat and back portions thereof with respect to the base.

2. In a chair of the class described, a supporting base comprising front, rear and side frame members, a combined seat and back unit including seat and back portions secured together in angular relation, a horizontally disposed member, mounted for relative rotary movement in a vertical plane and disposed in the lower rear corner of said unit, and an upright pivot pin pivotally supporting said member on the rear frame member and cooperating with said horizontally disposed member to permit swinging movement of said seat and back unit in a horizontal plane, thereby to permit reversing the seat and back portions of said unit with respect to the base and without detaching the unit therefrom.

3. In a chair of the class described, a supporting base, a combined seat and back unit including seat and back portions secured together in angular fixed relation, and pivot means located

on the rear portion of said base intermediately of the sides thereof for mounting said seat and back unit on the base, said pivot means adapted to rotate about vertical and horizontal axes whereby the seat and back unit is adapted for swinging movement in horizontal and vertical planes, thereby to permit reversing the position of said seat and back unit upon the base without detaching it therefrom.

4. In a chair of the class described, a supporting base, a combined seat and back unit including seat and back portions secured together in angular fixed relation, an upright pivot pin mounted on the rear portions of said base intermediately of the sides thereof, a member pivoted on said pin and adapted for swinging movement in substantially a horizontal plane, and means at the rear lower corner of said seat and back unit for pivotally connecting said unit to said member and cooperating with said pivot pin to permit swinging movement of the seat and back unit in horizontal and vertical planes, whereby the seat and back unit may be positioned to reverse the seat and back portions thereof with respect to the base.

5. In a chair of the class described, a supporting base comprising front, rear and side frame members, a combined seat and back unit including seat and back portions secured together in angular relation, an upright pivot pin mounted

in the rear frame member intermediately of the sides of the base, an elongated member pivotally mounted on said pivot pin and adapted for swinging movement in substantially a horizontal plane about the axis of the pivot pin, and means at the lower rear corner of the seat and back unit for pivotally connecting said unit to said member and whereby the unit is adapted for swinging movement in a vertical plane, said pivot pin and elongated member cooperating to permit swinging movement of the seat and back unit in horizontal and vertical planes, whereby said seat and back unit may be positioned at will, to reverse the seat and back portions thereof with respect to the base.
